UNITED STATES PATENT OFFICE

95,394

DESIGN FOR A SHOE

Evelyn Ziniti, New York, N. Y., assignor to Scholnick Shoe Co., Jamaica Plain, Mass., a corporation of Massachusetts

Application January 28, 1935, Serial No. 55,106

Term of patent 3½ years

To all whom it may concern:

Be it known that I, Evelyn Ziniti, a citizen of the United States, residing at New York, in the county of New York and State of New York, have invented a new, original, and ornamental Design for a Shoe, of which the following is a specification, reference being had to the accompanying drawing, forming a part thereof, in which

Fig. 1 is a view in side elevation of a shoe showing my new design, the opposite side of the shoe presenting substantially the same appearance as the side shown; and

Fig. 2 is a plan view of the forepart of the shoe.

I claim:

The ornamental design for a shoe substantially as shown and described.

In testimony whereof, I have affixed my signature hereto.

EVELYN ZINTTI.
